J. G. HOCK.
Gas Apparatus.

No. 19,777.

Patented March 30, 1858.

UNITED STATES PATENT OFFICE.

JOHN G. HOCK, OF NEWARK, NEW JERSEY.

GAS-GENERATOR.

Specification of Letters Patent No. 19,777, dated March 30, 1858.

To all whom it may concern:

Be it known that I, JOHN G. HOCK, of Newark, in the county of Essex and State of New Jersey, have invented certain new and useful Improvements in Apparatus for the Manufacture of Illuminating-Gas; and I do hereby declare that the following is a full, clear, and exact description of the same, reference being had to the accompanying drawings, making a part of this specification, in which—

Figure 1 is a vertical section of the apparatus complete. Fig. 2 is a vertical section of the retort and furnace, at right angles to Fig. 1, in the plane indicated by the line $x-x$. Fig. 3 is a horizontal section of the furnace, in the plane indicated by the line $y-y$, in Figs. 1 and 2. Fig. 4 is a plan of the gas-holder, condenser, and purifier. Fig. 5, 20 is a horizontal section of the furnace door frame.

Similar letters of reference indicate corresponding parts in the several figures.

My improvements are more particularly designed for small gasworks for dwelling houses and public buildings, though they are wholly or in part applicable to gas-works on a larger scale.

They consist in certain provisions for vaporizing the tar from coal or other gas and returning it in a state of vapor to the retort, to be decomposed and converted into gas, which improvement is also applicable to the vaporization of rosin oil or other substance 35 of a liquid state or capable of liquefaction by heat, previous to its introduction to the body of the retort, to be decomposed or converted into gas.

To enable others skilled in the art to make 40 and use my invention, I will proceed to describe its construction and operation.

A is the retort furnace, constructed with such an arrangement of flues (not necessary to be herein described) as to cause the products of combustion to take a circuitous direction around about the retort. The door of this furnace is lined with fire-clay inserted in a peculiar manner, to wit, by inclosing a slab p , of fire-clay in a double iron frame m, n , (as shown in Figs. 1 and 5,) the two parts of which frame are hinged together on one side by a hinge o , (Fig. 5.) The inner portion m , of this frame, which fits around the slab, is made entirely open on 55 the outer side to admit the slab, but has a small rim $6, 6$, on the inner side for the slab

to rest against, and the outer portion n , fits over the inner portion m , and is made with a plate 8 , to cover the exterior of the slab. The main hinge q , on which the door opens 60 is attached to the inner portion m , of the frame, which admits of the outer portion n , being opened while the door is in its place, for the purpose of introducing the fire-clay slab or replacing it by a new one, if at any 65 time necessary. The part n is secured to m , on the side opposite the hinge, after the slab has been introduced and shut up, by means of a bolt passing through loops $10, 10$, or by any other kind of fastening.

B , is the retort constructed with a raised chamber B^1 , on the top, near the rear end, and with a chamber C , extending from top to bottom at the extreme rear, the said chambers B^1 , and C , being both closed at the top 70 by a single cover D , which is movable when necessary. The chamber B^1 , which is in free communication with the main body B , of the retort, and with which the upper part of the gas outlet pipe E is connected, contains 75 a series of shelves a, a , on which to place lime or other purifying material, over which, by a proper arrangement of openings in the said shelves, the gas is caused to pass to effect its partial purification as it is about to 80 leave the retort by the pipe E . The chamber C has no communication with the main body B , of the retort, except at a passage p^1 , at the bottom and below a grating or perforated plate b , which is fitted to and supported in the retort near the bottom for the purpose of leaving an open space c , below the coal or other solid gas-making material with which the retort is charged, which material is intended to rest upon the said grating. This grating or perforated plate b , 85 may be constructed in two or more pieces so as to be capable of withdrawal at the mouth of the retort if necessary.

The chamber C , which is heated like the 100 main body of the retort, contains an upright vaporizer G , of conical, pyramidal, or other taper form, terminating in a point or nearly so at the top, substantially as represented in Fig. 1, said vaporizer being constructed of 105 metal either solid or hollow, and having a small gutter d , around its base; and above this vaporizer there is supported within said chamber C , a funnel H , to which the overflow of tar from the hydraulic main is all 110 conveyed by a pipe I . This tar, dripping through the bottom of the funnel on to the

top of the vaporizer, trickles slowly down the exterior surface of the latter, which being kept at a high temperature by the fire which almost entirely surrounds the vaporizing chamber C, effects the vaporization of the whole of this tar. The vapor thus produced, finding no other means of escape, passes into the space c, under the grating b, and escapes through said grating among the 5 coal or other substance in the retort, and is there decomposed by heat and converted into gas, which passes off by the pipe E, along with what is generated by the substance contained in the retort. The gutter 10 d, receives any tar that is not vaporized in the act of running down the surface of the vaporizer and prevents its falling on to the bottom of the retort and becoming carbonized, and retains it till it is vaporized. 15

K, is the movable head of the retort, which 20 is taken off to allow the charges of coal or other material to be introduced.

I do not claim, broadly, to be the first inventor of retorts, having perforated bottoms and chambers; nor do I claim the 25 chambers B', C, separately considered or when not arranged substantially as herein shown and described.

What I claim as my invention, and desire to secure by Letters-Patent, is:

The arrangement together of the main retort B, chambers B', C, and open space c, substantially as and for the purposes herein set forth.

JOHN GEORGE HOCK.
